UNITED STATES PATENT OFFICE.

MARSHALL SATTLEY, OF SPRINGFIELD, ILLINOIS, ASSIGNOR TO THE SATTLEY MANUFACTURING COMPANY, INCORPORATED, OF SAME PLACE.

CULTIVATOR.

SPECIFICATION forming part of Letters Patent No. 537,074, dated April 9, 1895.

Application filed July 18, 1894. Serial No. 517,949. (No model.)

To all whom it may concern:

Be it known that I, MARSHALL SATTLEY, of Springfield, in the county of Sangamon and State of Illinois, have invented certain new and useful Improvements in Cultivators, of which the following is a specification.

This invention relates to straddle row cultivators. It is embodied in the structure hereinafter described, and it is defined in the appended claims.

In the drawings forming part of this specification, Figure 1 is a side elevation of a cultivator beam equipped in accordance with my invention. Fig. 2 is a plan of the beam and adjuncts. Fig. 3 is a perspective representation of an end of a cross bar of the cultivator, with a specific form of standard fastened thereto. Fig. 4 is a perspective representation of the bracket and bar used to couple the cross bar to the draft beam.

The draft beam is shown at 1 and the cross bar at 2. The coupling between the beam and the bar comprises the bracket 3 and the bar 4, joined together pivotally at the rear of the bracket and the center of the bolt by means of the vertical pin 5. The bracket has a hole 3^a through which the bars of the draft beam a bolt extends and forms a pivot; and it also has a set of holes 3^b which enables the bracket to be bolted on the beam at various degrees of inclination. The ends of the bar have each a set of holes, as shown at 6, which enable the cross bar to be adjusted with the same movement and with the same result as if it were swung at its longitudinal center on a transverse horizontal pivot; the connection of the cross bar with the bar 4 being made by means of bolts that extend through the cross bar and through the holes 6. The

standards 7 are twisted at 7^a to bring the upper parts in line with the cross bar and the lower parts in line with the direction of motion, and they have the rectangular extensions 7^b which fit against the upper surface of the bar. They are secured to the bar by bolts, as shown, and the bolts are aided in forming secure and rigid connections by the overlapping extensions 7. The shanks are secured to the standards by means of the customary bolts and break pins. A link 10 con-

ncts loosely at one end with bracket 12 on the cross bar, and at the other end with bracket 11 on the draft beam. The function of the link is to hold the cross bar obliquely across the line of travel. It is sufficiently loose in its connections with the brackets to permit tilting adjustment of the bar, and either of the brackets may be adjusted lengthwise of the beam or the cross bar, as the case may be, in order to vary the degree of obliquity of the cross bar. The clevis-like bracket 13 provides for connecting the draft beam with the arch frame of a cultivator, and permits vertical adjustment in the rear end of the beam and consequent variation in the depth of cultivation. A handle is shown at 14, in Fig. 1, and a brace bar for the handle is shown at 15.

The mechanism described comprises one half of the cultivating contrivances of a cultivator. The other half, not shown, should have the cross bar reversely arranged, and both are to be connected with the arch frame in the customary, or any desirable, manner.

Adjustment of the draft beam in bracket 3 inclines the shovels forward or backward to adapt the cultivator to different kinds and conditions of soil, but has the effect of raising the shovels at one end of the cross bar while depressing those at the other end. To neutralize this effect when it is desired that the shovels shall run level, and to provide for such tilting when, to favor the roots or for any other reason, it is desirable that the shovels at one end shall run deeper than those at the other, the adjustment of the cross bar on bar 4 is provided for, and, as before stated, the link permits all adjustments while holding the cross bar in such position that the shovels will run one in advance of another.

Having thus described my invention, I claim as new and desire to secure by Letters Patent—

1. In a cultivator, the combination of a draft beam, a bracket having vertical swinging adjustment on the rear end of the beam, and an oblique, tiltable, shovel-carrying cross bar connected with the bracket, substantially as set forth.

2. In a cultivator, the combination of a draft beam, a bracket having vertical swinging ad-

justment on the rear end of the beam, a bar connected with the bracket by means of a vertical pivot pin, an oblique, tilttable, shovel-carrying cross bar connected with the bar, 5 and a swinging link connecting the bar with the beam in a manner to preserve the obliquity of the bar, substantially as set forth.

In testimony whereof I sign my name in the presence of two subscribing witnesses.

MARSHALL SATTLEY.
